UNITED STATES PATENT OFFICE

122,131

DESIGN FOR A RUBBER HEEL

Ray E. Sannar, Elyria, Ohio

Application July 15, 1940, Serial No. 93,656

Term of patent 14 years

To all whom it may concern:

Be it known that I, Ray E. Sannar, a citizen of the United States, residing in Elyria, in the county of Lorain and State of Ohio, have invented a new, original, and ornamental Design for Rubber Heel, of which the following is a specification, reference being had to the accompanying drawing, forming a part thereof.

Fig. 1 is a plan view of a rubber heel showing my new design;

Fig. 2 is a side elevation thereof; and
Fig. 3 is a section taken on the line 3—3 of
Fig. 1 thereof.

I claim:
The ornamental design for a rubber heel, substantially as shown.

RAY E. SANNAR.
